UNITED STATES PATENT OFFICE.

OLIVER P. FRITCHLE, OF DENVER, COLORADO, ASSIGNOR TO THE FRITCHLE AUTOMOBILE AND BATTERY COMPANY, OF DENVER, COLORADO, A CORPORATION OF COLORADO.

SAFETY-BRAKE AND LOCK-SWITCH MECHANISM FOR ELECTRIC AUTOMOBILES.

972,845.

Specification of Letters Patent. Patented Oct. 18, 1910.

Application filed December 27, 1903 Serial No. 634,972.

To all whom it may concern:

Be it known that I, OLIVER P. FRITCHLE, a citizen of the United States, residing at Denver, in the county of Denver and State 5 of Colorado, have invented certain new and useful Improvements in Safety-Brake and Lock-Switch Mechanism for Electric Automobiles, of which the following is a specification.

10 My invention relates to a device for breaking the circuit when the brake-mechanism is set on an electric automobile.

The device is intended for use with controllers of the kind shown in my application Ser. No. 435,605, filed May 29, 1908, 15 and adds an additional safeguard to the automatic switch-locking devices there shown.

Referring to the drawings:—Figure 1 is 20 a perspective view of the device as a whole; Fig. 2 is a sectional elevation; Fig. 3 is a perspective view, showing the arrangement of the parts with relation to the seat of the automobile; and Fig. 4 is a detail perspective view of the locking mechanism.

Referring to Fig. 1, the brake mechanism is operated by means of a foot-piece 1, on the top of a lever 2, pivoted at its bottom. A rod 3 connects lever 2 with an arm 4, se- 30 cured to the shaft 5, which carries an arm 6, to which the brake rod, (not shown) is connected. 7 is a toothed sector also se- cured to the shaft 5.

8 is a pawl pivoted on a block 9, which 35 forms one of the supports for the shaft 5. To the outer end of the pawl is pivotally connected a rod 10, arranged to slide in guides 11. A spring 12 is mounted between the lower guide 11 and a lug 13, and tends 40 to keep the rod normally raised. At the top of the rod 10 is a handle 14 having an arm 15, laterally projecting over the switch-lever 22. This switch-lever 22 has a pin 73, which in the lowermost position of the switch-lever 45 22 can be engaged by a hook 72, on a shaft 16, mounted on and projecting from the base-board A of the controller. A spring 18 tends to rotate the shaft 16 and hook 72 to- 50 ward its position of engagement with pin 73. The upper portion of this hook is inclined as shown, so that the pin 73 as it moves downwardly will push the hook to one side, and pass under the hook. Secured to shaft 16, is a short arm 71, arranged to be

engaged by the rod 75 projecting through 55 an opening in the normally rigidly held arm 69. The rod 75 is carried by an arm 41 pivoted to the arm 69, the two arms being normally separated by a strong spring 42, which holds the arm 41 against the back- 60 stop 74. This mechanism is shown in detail in my application, Ser. No. 435,605, above referred to, as are the controller handle F and attached parts comprising a bar G carrying the contact blade 43 which engages a 65 series of contact fingers 17, a rod I connected to the bar G, and sliding bar 40, mounted in a guide 55. The end of this bar engages the bar 41, when the controller handle is swung over, and causes the rod 75 to move the arm 70 71 and shaft 16 to disengage the hook 72 from the pin 73.

In Fig. 4, I have shown a combination lock C, whose bolt D holds the switch arm 22 down to prevent the closing of the switch. 75

The switch-arm 22, the brake setting arm or handle 14 and the combination lock, are preferably arranged, as shown in Fig. 3, near the middle portion of the seat, the controller handle being located at one side of 80 the seat, and the brake-operating foot-piece in the floor.

In operation of the device, the brake can be applied by a forward movement of the lever 2. A downward movement of the rod 85 10 by means of handle 14, will then set the brake by means of engagement of pawl 8 with sector 7. In this downward movement of the rod 10, the arm 15 engages the switch arm and opens the switch 22, thus cutting 90 off the current and setting the brake by a single movement. In this position, the switch-arm is also locked down by the hook 72, so that the current cannot again be turned on until the brake-setting rod has 95 been released, and the controller returned to the off-position. The combination-lock also locks the switch lever, so that provision is made not only against unauthorized use of the machine, but also against possible 100 carelessness of the operator, who cannot turn on current as long as the brakes are set, and even if he releases the brake-setting device, cannot close the main-switch until the controller has been returned to the no-current 105 position.

It will be noted that this brake-setting device does not interfere with the ordinary

use of the brake, while the current is on, but only when it is desired to set the brakes, as for an emergency stop, or when it is desired to hold the machine still, as when stopped on a down grade.

I claim:

1. The combination with a switch-arm of a brake-setting device and a controller mechanism, each having a part engaging the switch-arm to hold it in open position.
2. The combination with a switch-arm of a brake-setting device and a controller mechanism and a lock, each having a part engaging the switch-arm to hold it in open position.
3. The combination of a switch-arm, and a brake-setting device comprising an operating rod having an arm to hold the switch-arm open when the brake is set, and arranged to be disengaged therefrom when the brake is released.
4. The combination of a switch-arm, and

a brake-setting device comprising an operating rod having an arm to hold the switch-arm open when the brake is set, a controller mechanism comprising a handle and having a holding device to engage the switch-arm and mechanism connected to the controller handle for disengaging such holding device.

5. A safety device for electric automobiles, comprising a switch-arm, a spring-pressed hook engaging the arm, a controller-mechanism having a handle and connections therefor to disengage the hook when the controller is in off position, a brake setting device, an operating rod therefor, and an arm connected to said rod to operate the switch-arm to open the switch.

In testimony whereof, I affix my signature in presence of two witnesses.

OLIVER P. FRITCHLE.
